UNITED STATES PATENT OFFICE.

SAMUEL HARRISON EVERETT, OF BROOKLYN, NEW YORK, ASSIGNOR, BY MESNE ASSIGNMENTS, TO WESTERN ELECTRIC COMPANY, INCORPORATED, A CORPORATION OF NEW YORK.

TELEPHONE SIGNALING SYSTEM.

1,293,390.

Specification of Letters Patent.

Patented Feb. 4, 1919.

Application filed March 11, 1915. Serial No. 13,696.

To all whom it may concern:

Be it known that I, SAMUEL HARRISON EVERETT, a citizen of the United States, residing at Brooklyn, in the county of Kings and State of New York, have invented certain new and useful Improvements in Telephone Signaling Systems, of which the following is a full, clear, concise, and exact description.

10 This invention relates to telephone signaling systems and more particularly to ringing circuits with which may be associated sources of ringing current of widely different frequencies and relays for tripping or disconnecting the ringing current from the called line upon the response of the subscriber.

It is an object of this invention to provide a signaling circuit in which there is a 20 relay which will operate on direct current or on direct current upon which is superimposed alternating currents of widely different frequencies, but which will not operate on alternating currents alone, of the frequencies used in harmonic signaling.

In accordance with this invention, a signaling circuit is provided with an electromagnetic relay having a core upon which there is an energizing winding connected in 30 the circuit and positioned intermediate the ends of the core and having closed circuit coils mounted on the core, one upon each side of the energizing winding. Preferably these closed circuit coils consist of large masses of copper. These masses are so proportioned and the energizing winding is so positioned that, when the energizing winding is traversed by both direct current and superimposed alternating current, the leakage effect upon the core due to alternating currents of the higher frequencies is reduced to such a point as to permit the operation of the relay but not to such a point as to permit premature operation on alternating currents of the lower frequencies.

This invention is illustrated in the accompanying drawing, in which—Figure 1 is a side elevation of a tripping relay embodying this invention; Fig. 2 is a side elevation, partly in section, of the tripping relay shown in Fig. 1; and Fig. 3 shows the tripping relay of the invention in a multi-frequency ringing circuit associated with the calling end of a cord circuit, and a sub-

scriber's telephone line to which the calling end of the cord circuit may be connected.

As shown in Figs. 1 and 2, the tripping relay embodying the present invention consists of a core 5, about which is placed an energizing winding 6 positioned intermediate the ends of the core 5. There is also mounted upon the core 5, closed circuit coils 7 and 8, one on each side of the energizing winding 6.

These closed circuit coils 7 and 8, consist 65 preferably of copper tubes of large mass. It is obvious, however, that these coils 7 and 8, could very well be made up of a plurality of annular disks or rings, or of bare wire. The energizing winding 6, the core 5 and 70 the closed circuit coils 7 and 8 may be suitably separated by means of insulating material 9. Near one end, the core 5 is provided with a collar 10, separated from the closed circuit coil 7 by an insulating washer 11. 75 In the washer 11, there are terminals 15 and 16, suitably mounted to which are attached leads for the energizing winding 6.

The core 5 together with the above described parts mounted thereon is inclosed in 80 a shell 17 of magnetic material, openings being provided in the closed end 18 thereof with which register the terminals 15 and 16 and the end of the core 5. The core 5 is firmly secured to the end 18 of the shell 85 17 by means of a nut 19 having screw threaded engagement with the end of the core. A terminal 20, to which one lead of the circuit to be controlled is attached, is suitably secured to the core 5. Near the 90 open end of the shell 17, there is mounted upon the shell a yoke 21 of non-magnetic material to which is pivoted an armature 22 in operative relation to the end of the core 5. A spiral spring 25, secured at one 95 end to a finger 26 mounted on the shell 17, and at the other end to a finger 27 attached to the armature 22, normally holds the armature 22 away from the end of the core 5, as in Fig. 1. A contact spring 28, mounted 100 on the armature 22 is electrically connected to the terminal 20 through the relay structure. A terminal member 29, to which is attached the other lead of the circuit to be controlled, is mounted upon but insulated 105 from the shell 17. In the forward end of terminal member 29 which is bent, as shown in Fig. 1, is mounted an adjustable contact

stud 30. Normally the action of spring 25 maintains contact spring 28 and contact stud 30 in engagement.

In Fig. 3 is shown a subscriber's telephone line terminating in a jack 35 and the calling end of a cord circuit with which is associated alternating current generators of different frequencies and necessary apparatus including the tripping relay embodying this invention for connecting any of the generators to the telephone line and disconnecting any particular generator from the telephone line.

Upon insertion of the calling plug into the jack 35 of the wanted subscriber's line, a circuit is completed from battery 36 through the winding of relay 37, sleeve contacts of the calling plug and jack and the winding of the usual cutoff relay 38 to ground, operating relay 38, thereby removing the usual line relay from the limbs of the subscriber's telephone line. Current in the above traced path also actuates relay 37 which completes a circuit from battery 36, through contact 40 of relay 37, contact 41 of relay 42 (which is the tripping relay embodying the present invention), contact 43 of relay 44, and winding of relay 45 to ground, actuating relay 45, which opens the tip and ring strands of the cord circuit and connects the tip side to ground at contact 46 and the ring side to the winding of tripping relay 42 through contact 47. In Fig. 3 there are shown four alternating current generators of different frequencies, each having one side connected through interrupters 50, 50 and a battery 48 to ground, the other side of each generator being connected to normally open contacts of a locking ringing key 49. A second interrupter 56 may be provided for each generator, the two interrupters associated with each generator being so related that when interrupter 50 closes the circuit from battery 48 to the generator, interrupter 56 opens the parallel path from battery 48 to the open contact of ringing key 49; also that when interrupter 56 closes the path from battery 48 to the open contact of ringing key 49, interrupter 50 opens the parallel path through the generator. With the interrupters associated with each generator so related, there are provided periods when direct current only is available at the ringing key alternating with periods when direct current upon which is superimposed alternating current is available at the ringing key.

In harmonic ringing systems, it is common practice to use generators, which generate alternating currents of $16\frac{2}{3}$, $33\frac{1}{3}$, 50 and $66\frac{2}{3}$ p. p. s., and these in Fig. 3 are respectively represented by reference numerals 51, 52, 53 and 54. After insertion of the calling plug into the jack 35 of the wanted line, the operator operates a button of lock-

ing ringing key 49 connecting to one of the middle contacts of this key ringing current of the frequency to which the bell at the wanted substation is tuned. Suppose that the left hand alternate contact of key 49 has been closed, a circuit is then closed from grounded battery 48, through interrupter 50, generator 51, left hand alternate contact of ringing key 49, winding of tripping relay 42, contact 47 of relay 45, ring side of line, bell 60, condenser 61, tip side of line and contact 46 of relay 45 to ground. It may be, however, that, when the left hand alternate contact of ringing key 49 is closed, the path through interrupter 50 is open and that through interrupter 56 is closed, in which case ringing of the bell 60 would not start immediately. Ringing starts, in this case, when interrupter 50 closes the circuit through the generator 51 and after interrupter 56 opens the parallel path. With a relation between interrupters 50 and 56 such as above described, direct current, and direct current with alternating current superimposed thereon are alternately connected to the subscriber's line. The condenser 61 at the subscriber's station prevents the passage of direct current. Tripping relay 42 does not operate when in series with the bell 60 and condenser 61. However, when the receiver is removed from the switchhook, a low resistance path is closed, whereupon tripping relay 42 operates, opening the short circuit of relay 44. Relay 44 operates and locks up, short-circuiting relay 45, which releases to disconnect the ringing current from the line. The removal of the receiver at a called subscriber's station either during the period when direct current only is connected to the line or during the period when direct current with alternating current superimposed thereon is connected to the line causes the operation of tripping relay 42.

Relays embodying the present invention, must meet very severe service requirements, in that the relay must not operate when traversed by alternating currents of the frequencies used in harmonic signaling, but must operate the instant an alternating current bell and a condenser at the subscriber's station are removed from the circuit, as by removing the receiver from the switchhook, and a path is closed for direct current, or for direct current upon which is superimposed alternating current of any of the frequencies used in harmonic signaling. A relay, embodying this invention has been constructed to meet the following conditions of service.

(1) It must operate when traversed by direct current

(2) It must operate when in series with a 1000 ohm line at the end of which is a ringer or bell tuned to operate on $66\frac{2}{3}$ p. p. s. alternating current and when traversed by

direct current at a pressure of 40 volts upon which is superimposed $66\frac{2}{3}$ p. p. s. alternating current.

(3) It must operate when in series with a line of practically no resistance to which are connected 8 ringers or bells, 2 of which are tuned to operate on $66\frac{2}{3}$ p. p. s. A. C., 2 on $33\frac{1}{3}$ p. p. s. A. C., 2 on 50 p. p. s. A. C. and 2 on $66\frac{2}{3}$ p. p. s. A. C.—and when traversed by direct current at a pressure of 40 volts upon which is superimposed $66\frac{2}{3}$ p. p. s. alternating current at a pressure of 168 volts.

(4) It must not operate when in series with a line of practically no resistance to which are connected 8 ringers each having a condenser in series therewith, 2 of the ringers being tuned to operate on $16\frac{2}{3}$ p. p. s. A. C., 2 on $33\frac{1}{3}$ p. p. s. A. C., 2 on 50 p. p. s. A. C. and 2 on $66\frac{2}{3}$ p. p. s. A. C. and when traversed by $16\frac{2}{3}$ p. p. s. A. C. at a pressure of 168 volts.

The dimensions of the important elements of the relay which meets the above requirements are as follows:—

Length of core 5 from collar 10 to armature end	3.14 "
Diameter of core 5	.37 "
Length of closed coil 7	.780 "
Diameter of closed coil 7	.715 "
Length of closed coil 8	1.687 "
Diameter of closed coil 8	.870 "

Energizing winding consists of 3300 turns of #35 insulated wire.

Relays have been produced to operate when traversed by direct current only or by direct current upon which is superimposed alternating current of a particular frequency and not to operate when traversed by only alternating current of the particular frequency, but no relay has heretofore been produced which would operate when traversed by direct current upon which is superimposed alternating current of any of a plurality of widely different frequencies. In accordance with the present invention such a relay has been produced. Such a relay is of very great importance and utility in multi-frequency ringing circuits of telephone signaling systems. Whereas heretofore it has been necessary to use a separate tripping relay in a cord or trunk circuit for each frequency of alternating current, it is possible by the utilization of the tripping relay embodying the present invention to use only one tripping relay in a cord or trunk circuit for all frequencies of alternating current.

60 In Fig. 3, while for sake of simplicity only one alternating current bell has been shown connected to the subscriber's line, it is to be understood that a plurality of such bells may be connected therewith, it being usual 65 in party line systems to have the different

bells tuned to respond to different frequencies of alternating current.

What is claimed is:

1. In a telephone signaling system, a source of intermittent signaling currents of 70 different frequencies, signals selectively responsive to the different signaling currents, a signaling circuit for selectively connecting said current source with said signals in accordance with the signal to be operated, means for applying direct current to said signaling circuit in either a signaling or a non-signaling interval, and electromagnetic means for opening said signaling circuit, said electromagnetic means including an armature, a winding included in the signaling circuit, and means for rendering said armature non-responsive to currents of the different frequencies through said winding but responsive to direct current alone or to direct current upon which is superimposed any of the different frequencies of alternating current.

2. In a telephone signaling system, means for supplying intermittent signaling currents having frequencies of approximately $16\frac{2}{3}$, $33\frac{1}{3}$, 50 and $66\frac{2}{3}$ periods per second, signals selectively responsive to different signaling currents, a signaling circuit for selectively connecting said current source supplying means with said signals, means for applying direct current to said signaling circuit in either a signaling or a non-signaling interval, and electromagnetic means for opening said signaling circuit, said electromagnetic means including an armature, a winding included in the signaling circuit, and means for rendering said armature non-responsive to currents of said different frequencies through said winding but responsive to direct current alone or to direct current upon which is superimposed alternating current of any of said different frequencies.

3. In a telephone signaling system, a source of intermittent signaling currents of 110 different frequencies, signals selectively responsive to the different frequencies, a signaling circuit for selectively connecting said current source with said signals in accordance with the signal to be operated, means for applying direct current to said signaling circuit in either a signaling or a non-signaling interval, and electromagnetic means for opening said signaling circuit, said electromagnetic means including an armature, a winding included in the signaling circuit, and closed secondary coils for rendering said armature non-responsive to currents of the different frequencies through said winding but responsive to direct current alone or to direct current upon which is superimposed signaling current of any of the different frequencies.

4. In a telephone signaling system, a source of signaling currents of different fre-

4
quencies, a source of direct current, a signaling circuit connected to be traversed by signaling current of any one of said frequencies, by direct current or by both, a relay, 5 an energizing winding therefor in said circuit, and closed circuit secondary coils associated with said relay for rendering said relay non-responsive to signaling current of any of said frequencies traversing said energizing winding, said relay being respon-

sive when said winding is traversed by direct current or by direct current and signaling current of any of said frequencies.

In witness whereof, I hereunto subscribe my name this 10th day of March A. D. 1915. 15

SAMUEL HARRISON EVERETT.
